UNITED STATES PATENT OFFICE.

EDWARD G. ROWLEY, OF BELLEVILLE, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed March 23, 1925. Serial No. 17,554.

This invention relates to sound-deadening casings for small typewriting machines in which the machine is completely enclosed within the casing except for the keyboard-extension which protrudes therethrough; and one of its features is to deaden the noise arising from the operation of the machine.

The casing comprises a body-part fast to a base-plate upon which the machine is mounted, and is provided with a cover which may be opened to manipulate the work-sheet. In order that the carriage of the machine may be controlled from the outside of the casing and thus eliminate the necessity of opening the cover to return the carriage, there is provided mechanism operatively connecting a hand-lever to the carriage. Said lever is pivotally mounted on the front wall of the casing adjacent the keyboard of the machine and at the right thereof. Upon depressing the lever, a drum around which a cord or tape is wound is made to rotate, thus pulling on the cord and consequently returning the carriage. Due to the peculiar design of the Underwood machine, in which the carriage is returned simultaneously with the line-spacing of the work-sheet by manipulating the line-spacing lever, the cord may be fast to the line-spacing lever, and in this manner the work-sheet may be line-spaced while the carriage is returned.

Another feature relates to the provision of an indicating scale on the casing and in front thereof, which scale co-operates with an indicating pointer fast to the carriage-return lever. The pointer is located to indicate the position of the carriage relatively to the printing point, and said scale may substitute the regular scale in the machine.

The carriage-return lever is provided with a thumb-piece at the end thereof, upon which pressure is applied to return the carriage. Said thumb-piece is rockably mounted upon the lever, and is provided with mechanism whereby the thumb-piece may be held in its horizontal position throughout its swing. Said mechanism may include a parallelogrammatic link connecting a downwardly-extending portion of the thumb-piece to a fixed stud upon the front wall of the casing.

Another feature relates to the construction of the casing, and more particularly to means for mounting the machine therein.

55 The frame of the machine is snugly fitted

into a felt-padded metal box which is fast to a base-board, and then the four sides of the casing are fastened to the base-board by means which may include straps between the front and rear walls having holes therein to engage studs fast to the base-board.

Another feature of the invention relates to the provision of means to enable the work-sheet on the carriage to move freely therewith. To this end, the felt lining at the back and top of the casing is covered with a plate of smooth material, to present an even surface to the work-sheet, both when fed around the platen of the machine, and when letter-spacing the carriage, in which cases the work-sheet might drag against the ordinarily rough surface of the felt.

Other features and advantages include improved means to retain the cord on the drum which returns the carriage. Said means comprises a light spiral spring to take up the slack of the cord, and a guard around the drum to hold the cord within a groove cut into the periphery of the drum. Said guard is provided with a cut-out through which the cord extends and is connected to the line-spacing lever. The spring tends to rotate the drum-carrying shaft in the carriage-returning direction and is sufficiently weaker than the line-space-lever-spring to permit the lever to return to normal position after a line-spacing operation. However, the cord is always kept taut and due to this fact the pointer always indicates accurately on the scale the exact position of the carriage with respect to the printing point.

Other features and advantages will hereinafter appear.

In the accompanying drawings,

Figure 1 is a perspective view of the sound-deadening casing, showing the machine therein and the keyboard protruding therethrough.

Figure 2 is a cross-sectional view, in elevation, showing an Underwood Portable typewriting machine within the casing.

Figure 3 is a front view, in elevation, and shows the carriage-return lever and the indicating scale co-operating therewith.

Figure 4 is a cross-sectional view, in elevation, showing the machine in the casing and the carriage-return mechanism.

Figure 5 is a cross-sectional plan view through the line 5-5, of Figure 3.

Figure 6 is a fragmentary end view, in elevation, showing an auxiliary arm connecting the line-spacing lever of the machine to the carriage-return mechanism.

5 Figure 7 is a perspective view of the auxiliary lever.

Figure 8 is a fragmentary view, in elevation, showing the drum and a casing to hold the cord in the groove around the periphery of said drum.

10 Figure 9 is a cross-sectional view, in elevation, through the line 9—9 of Figure 3.

Figure 10 is a cross-sectional view, in elevation, showing the cord-tensioning spring, 15 and the means to fasten the enclosing barrel to the rear wall of the casing.

Figure 11 is a front view of the cord-tensioning spring on the line 11—11 of Figure 9, looking in the direction of the arrows.

20 Figure 12 is a perspective view of the base-board and the felt-padded metal box into which the frame of the machine is fitted.

Figure 13 is a dismembered perspective view, 25 showing the felt pads upon which the machine rests.

In order to deaden the sound arising from the operation of the machine, there is provided a sound-deadening casing which completely encloses the machine except for a keyboard-extension 10, which protrudes through an opening 11 in the front wall 12 of the casing. Said casing is lined with layers of sound-deadening material to reflect the sound waves and to confine them within the casing. As shown in the drawings the casing comprises a base-board 13, a box 14 containing the frame of the machine, sound-confining walls fast to the base-board, and a cover 15 pivotally mounted upon the rear wall 16.

The machine is located in the box 14 which hugs the frame thereof, which box is in turn fast to the base-board 13. Referring more particularly to Figures 12 and 13, in which the dismembered elements of the box are shown, it will be noted that there is provided a base-plate 17 from which ears 18 are upwardly bent, forming the walls for supporting the machine. Said base-plate is underlined with a layer of felt 19 which extends upwardly to cover the ears 18. Said layer of felt is bent at 20 and extends downwardly, providing a lining 21 on which the frame of the machine bears. The base-plate 17 is covered with a plurality of layers of felt to insulate the feet 22 of the machine from contact with the base-board, to thus prevent the transmission of sound therethrough. There are three layers of felt shown in the drawings, indicated by the numeral 23, the upper layer being provided with holes 24 for receiving the feet 22, and with an elongated rectangular hole 25, to clear some of the mechanism which over-

extends the frame of the machine. The three layers are further provided with a cut-out 26 at the rear into which the rear ear of the box 14 engages, and with cut-outs 27 for receiving the side ears of said box. 70 For engaging the front wall 12 of the casing, and thus prevent the emission of sound through the front, there are provided notches 28 cut into the felt layers and into the base-plate. 75

The box is located relatively to the base-board 13 by means of studs 29 which are fast to the base-board and extend through holes 30 in the base-plate and in the felt layers. In this manner a positive connection 80 is provided between the base-board and the frame of the machine through the box 14, the felt-padded ears of which bear upon the walls of the frame.

In order to facilitate the assembling of the machine into the casing, the base is provided with threaded studs 31 fast thereto, said studs being designed to engage holes in straps 32, which extend between the front and rear walls of the casing, to which they are fastened. In this manner the casing may be easily detached from the base-board by loosening finger-screws 33, and by moving the casing upwardly away from the board. It will be noted that the rear wall of the casing is comparatively higher than the front wall, in order to incline the cover 15 downwardly and to render the work-sheet more visible through an aperture 34 in the cover. Said aperture is enclosed by means of a glass plate 35 to prevent the emission of sound therethrough. The glass plate is fitted into depressions 36 in the cover, and is fastened thereto by means of screws 37 which hold clips 38 bearing upon the edge 100 of the glass. 105

To further prevent the emission of sound, the walls of the casing are provided with a felt lining 39 completely covering the inner sides of the walls, and presenting a refractory surface to the sound waves emanating from the machine. The cover is likewise lined with a layer of felt 40, to thus prevent the transmission of sound therethrough.

In the Underwood machine there is provided a carriage 41 mounted upon rails, which carriage is arranged to letter-space after each key-depression. For the purpose of line-spacing the work-sheet which is placed around a platen 42 on said carriage, 110 there is provided a line-space lever 43 operatively connected to a ratchet-wheel 44 fast to a shaft 45 upon which the platen is revolvably mounted. The line-space lever is furthermore arranged to be used as a means 115 to return the carriage to its starting position. In order to eliminate the necessity of opening the cover 15 after each line of typing to space the work-sheet and to return the carriage, means are provided whereby 120 125 130

the carriage and the platen may be controlled from the outside of the casing. To this end, there is provided a revolvably mounted drum 46 within the casing, said drum being operatively connected to the line-space lever on the carriage by means of a strap or cord 47 wound around the drum. In this manner, when the drum is rotated and the cord is wound therearound, the carriage will be moved towards the drum, consequently returning the carriage to its normal position. The drum 46 is revolvably mounted upon a shaft 48 journaled in the front and rear walls of the casing at 49. The shaft 48, which carries the drum 46, is operatively connected to a lever 50 by means shown in Figure 4. Said means may include a pinion 51 fast to the shaft 48 and meshing with an internal gear 52 fast to 20 a supporting disk 53, which is in turn fast to a shaft 54. Said shaft 54 extends outwardly through the front wall of the casing upon which it is journaled, and is provided with the lever 50 fast thereto. Referring 25 more particularly to Figures 5 and 9, it will be noted that the shaft 54 is rotatably mounted in a supporting sleeve 55, which is fast to the front wall of the casing by means of a collar 56 driven thereinto. The 30 shaft 48 extends from one side to the other of the casing, and passes through the disk 53 which is provided with a circular slot 57 to clear the shaft.

For the purpose of taking up the slack of 35 the cord and to have it evenly tensioned between the lever and the drum, there is provided a spring 58, shown in Figure 10. Said spring is shown in the form of a spiral wound around the shaft 48 and having its 40 inner end fast thereto. The outer end of the spring is fast to a barrel 59, which is, in turn, fast to the rear wall of the casing, and incidentally serves as a bearing for the shaft 48. Said barrel is fast to a bushing 45 60, and the bushing is fastened to the rear wall by means of a recess 61 and a nut 62 which holds the bushing fast to the wall. In order to render the spring adjustable to thus regulate the tension on the cord, there 50 is provided a sleeve 63, upon which the inner end of the spring is fastened by means of rivets 64. Said sleeve may be rotated on the shaft to the desired position, and then set by means of a screw 65. It will be 55 noted that the sleeve is provided with an integral disk 66 which fits into the barrel 59, thereby enclosing the spring 58 between the barrel and the disk. The spring 58 keeps the cord 47 taut in all positions of the carriage.

In order to effectively hold the cord upon the drum in such cases when the tension of the cord may be released, there is provided a groove 67 cut into the outer rim of the 60 drum 46, which is covered with a guard 68

over the periphery of the drum, thus enclosing the cord in the groove. The guard is provided with an opening 69, through which the cord passes to the outside of the drum. It will be noted that the drum is provided 70 with a hub 70, into which a set-screw 71 fits, to fasten the drum upon the shaft 48. The guard is held in a fixed position relatively to the drum by means of a pin 72 fast thereto and engaging a hole 73 in a 75 spring 74 fast to the wall of the casing by means of rivets 75.

To facilitate the adaptation of the machine to be used within the casing, and in order to reduce alterations required to a 80 minimum, there is provided a line-space arm 76, shown in Figure 7, which is designed to lower the anchoring point of the cord, and thus hold the cord in a horizontal position below the printing line. Said arm 76 is fast 85 to the hub of the regular line-space lever 43 by means of a screw 77 and a pin 78 which engages the lever 43. The arm 76 terminates with an enlarged portion 79, into which a hole 80 is pierced to receive the end 90 of the cord 47.

To facilitate the positioning of the carriage relatively to the printing point, there is provided a circular scale 81, cooperating with a pointer 82 fast to the lever 50. Said 95 scale 81 is provided with graduations corresponding to the graduations on the regular scale on the carriage, which it may substitute. The scale is fast to the front wall of the casing by means of screws 83. By reason of the fact that all slack is eliminated from the cord 47, the pointer 82 always indicates on the scale 81 the exact position of the carriage with relation to the printing point.

The carriage-return lever 50 is provided with a thumb-piece 84 at the end thereof, upon which pressure is applied to return the carriage. Said thumb-piece is rockably mounted upon a pivot 85 fast to the lever. 100 In order that the thumb-piece may maintain its horizontal position throughout the swing of the lever, there is provided a parallelogrammatic link 86, engaging with a hole 87 in a downwardly-extending portion 88 of the 105 thumb-piece. Said link is pivotally mounted on a stud 89 fast to the front wall of the casing. Referring more particularly to Figure 3, in which this mechanism is shown, it will be noted that in both extreme positions 110 115 shown the thumb-piece is in its horizontal position.

In order to facilitate the removing of the casing from its supporting base-board, the casing is provided with handles 90 at the 120 ends thereof, by means of which the casing may be separated from the base-board after disconnecting the cord from the line-space lever, and loosening the screws 33 which normally hold the casing on the base-board.

The platen of an Underwood Portable typewriter is much lower than in the standard machine, due to the compact or flat design, and when a standard typewriter sheet is inserted around the platen of the casing-enclosed portable machine the trailing portion of the sheet is of such length that it tends to become entangled in the space between the rear of the machine-frame and the casing-wall. To obviate such entanglement of the sheet there is provided a guide, preferably in the form of a downwardly-extending plate 95 fast to the rear wall of the casing. Said plate terminates with a half-round bend 96, and extends up at 97 bearing upon the outer face of the box 14, so as to form a lower pocket for the unused or trailing portion of the work-sheet, which lies in the pocket, as shown by a line indicated by the numeral 98 in Figure 2. A second plate 91 of smooth stiff material extending substantially the full width of the casing is fast to the cover at 92. The purpose of this plate is to guide the leading edge 93 of the work-sheet away from the felt covering and to deflect said edge downward. The plate has a concave cross-section, and overlaps plate 95 at 94.

Variations may be resorted to within the scope of the invention, and portions of the improvements may be used without others.

Having thus described my invention, I claim:

1. A sound-deadening casing for a typewriting machine, including a base-plate, means for positioning the machine on the base-plate, said means including sound-deadening walls for receiving the machine and snugly fitting the frame thereof, and a detachably mounted enclosure including four upstanding walls and a cover therefor, the cover being swingably mounted upon the rear wall of said enclosure and the front wall being provided with an aperture 45 through which the keyboard of the machine protrudes.

2. A sound-deadening casing for a typewriting machine including a base-board and a detachably mounted enclosure therefor, both having a sound-deadening lining and the enclosure including a cover pivotally mounted upon the rear wall thereof, means for locating the machine on the base-board independently of the enclosure, said means including a wadded metal box having a base-plate from which upwardly-extending ears project, said ears serving as the locating means by lightly bearing upon the sides of the machine-frame, and means for insulating the machine from the base-board, said insulating means including a plurality of layers of sound-proof material supporting the feet of the machine and forming with said base-plate the bottom of the box.

3. A sound-deadening casing for a type-

writing machine including a base-board and a detachably mounted enclosure therefor, both having a sound-deadening lining and the enclosure including a cover pivotally mounted upon the rear wall thereof, means for locating the machine on the base-board independently of the enclosure, said means including a wadded metal box having a base-plate from which upwardly-extending ears project, said ears serving as the locating means by lightly bearing upon the sides of the machine-frame, the base-plate of the box being provided with a plurality of layers of sound-proof material supporting the feet of the machine, thereby insulating the machine from the base-plate and the base-board, and means for attaching and locating said box upon the base-board, said last-mentioned means including a plurality of studs fast to the base-board and projecting thereabove, said studs engaging with holes in the base-plate and with the layers of sound-deadening material.

4. A sound-deadening casing for a typewriting machine comprising a base-board, a wadded box for receiving the frame of the machine, said box being fast to the base-board, an enclosure completely encasing the machine, and manually-operable means whereby the enclosure may be attached to and detached from the base-board.

5. A sound-deadening casing for a typewriting machine comprising a base-board, a wadded box for receiving the frame of the machine, said box being fast to the base-board, an enclosure completely encasing the machine, and manually-operable means whereby the enclosure may be attached to and detached from the base-board, said means including straps connecting the front and rear walls of said enclosure and fast thereto, studs fast to the base-board and overextending the surface thereof, said straps having holes to receive the studs, and finger screws co-operating with thread-positions of the studs to fasten the straps upon the base-board.

6. A sound-deadening casing for a typewriting machine, the position of the carriage as indicated by the regular letter-spacing carriage-scale of the enclosed machine not being readily observable from the outside of the casing, means for operating the carriage of the machine from the outside of said casing, said means including a shaft journaled in the front wall of the casing and extending therethrough, a hand-operable lever secured to the outside end of the shaft, a cord fast to the line-space lever of the carriage, operating connections between the inside portion of the shaft and the cord, a letter-spacing scale on the outside of the casing, and a pointer secured to the shaft adjacent said hand-operable lever to move only once from one end of the scale to the

other during each full traverse of the carriage and to indicate on the outside scale each letter-space position of the carriage relative to the printing point as indicated by the regular carriage-scale.

7. A sound-deadening casing for a type-writing machine completely enclosing the machine except for the keyboard-extension protruding therethrough, and means for operating the carriage of the machine from the outside of said casing, said means including a hand-operable lever adjacent the keyboard of the machine, said lever being pivotally mounted on a shaft journaled in the front wall of the casing and extending therethrough, a disk fast to the shaft within the casing, a gear sector fast to the disk and operatively meshing with a smaller gear fast to a second shaft journaled within the casing, a drum having a peripheral groove in which one end of a cord is fast and wound therearound, said drum being fast to the second shaft and the other end of the cord being fast to the carriage of the machine to draw the same toward the drum upon operation of the lever, means to hold the guard in a fixed position relatively to the drum which revolves therein to return the carriage.
8. A sound-deadening casing for a type-writing machine completely enclosing the machine except for the keyboard-extension protruding therethrough, and means for operating the carriage of the machine from the outside of said casing, said means including a hand-operable lever adjacent the keyboard of the machine, said lever being pivotally mounted on a shaft journaled in the front wall of the casing and extending therethrough, a disk fast to the shaft within the casing, a gear sector fast to the disk and operatively meshing with a smaller gear fast to a second shaft journaled within the casing, a drum having a peripheral groove in which one end of a cord is fast and wound therearound, said drum being fast to the second shaft and the other end of the cord being fast to the carriage of the machine to draw the same toward the drum upon operation of the lever, means to hold the guard in a fixed position relatively to the drum which revolves therein to return the carriage.
9. A sound-deadening casing for a type-writing machine completely enclosing the machine except for the keyboard-extension protruding therethrough, and means for operating the carriage of the machine from the outside of said casing, said means including a hand-operable lever adjacent the keyboard of the machine, said lever being pivotally mounted on a shaft journaled in the front wall of the casing and extending therethrough, a disk fast to the shaft within the casing, a gear sector fast to the disk and operatively meshing with a smaller gear fast to a second shaft journaled within the casing, a drum having a peripheral groove in which one end of a cord is fast and wound therearound, said drum being fast to the second shaft and the other end of the cord being fast to the carriage of the machine to draw the same toward the drum upon operation of the lever, means to hold the guard in a fixed position relatively to the drum which revolves therein to return the carriage.
10. A sound-deadening casing for a type-writing machine completely enclosing the machine except for the keyboard-extension protruding therethrough, and means for operating the carriage of the machine from the outside of said casing, said means including a hand-operable lever adjacent the keyboard of the machine, said lever being pivotally mounted on a shaft journaled in the front wall of the casing and extending therethrough, a disk fast to the shaft within the casing, a gear sector fast to the disk and operatively meshing with a smaller gear fast to a second shaft journaled within the casing, a drum having a peripheral groove in which one end of a cord is fast and wound therearound, said drum being fast to the second shaft and the other end of the cord being fast to the carriage of the machine to draw the same toward the drum upon operation of the lever, means to hold the guard in a fixed position relatively to the drum which revolves therein to return the carriage.
11. A sound-deadening casing for a type-writing machine completely enclosing the machine except for the keyboard-extension protruding therethrough, and means for operating the carriage of the machine from the outside of said casing, said means including a hand-operable lever adjacent the keyboard of the machine, said lever being pivotally mounted on a shaft journaled in the front wall of the casing and extending therethrough, a disk fast to the shaft within the casing, a gear sector fast to the disk and operatively meshing with a smaller gear fast to a second shaft journaled within the casing, a drum having a peripheral groove in which one end of a cord is fast and wound therearound, said drum being fast to the second shaft and the other end of the cord being fast to the carriage of the machine to draw the same toward the drum upon operation of the lever, means to hold the guard in a fixed position relatively to the drum which revolves therein to return the carriage.
12. A sound-deadening casing for a portable typewriting machine having a platen relatively near the base of the machine, said casing including a cover and completely enclosing the machine except for the key-

ing a hole designed to engage a pin protruding from said guard.

9. A sound-deadening casing for a type-writing machine completely enclosing the machine except for the keyboard-extension protruding therethrough, and means for operating the carriage of the machine from the outside of said casing, said means including a hand-operable lever adjacent the keyboard of the machine, said lever being pivotally mounted on a shaft journaled in the front wall of the casing and extending therethrough, a disk fast to the shaft within the casing, a gear sector fast to the disk and operatively meshing with a smaller gear fast to a second shaft journaled within the casing, a drum having a peripheral groove in which one end of a cord is fast and wound therearound, said drum being fast to the second shaft and the other end of the cord being fast to the carriage of the machine to draw the same toward the drum upon operation of the lever, means for holding the cord within the groove, and means to take up the slack of the cord, said last-mentioned means including a spring operatively mounted on said shaft, said spring having its inner end adjustably fastened to the shaft and its outer end fast to a barrel for encasing the spring, said barrel being in turn fast to the casing.

10. A sound-deadening casing for a type-writing machine completely enclosing the machine except for the keyboard-extension protruding therethrough, means for operating the carriage of the machine from the outside of said casing, said means including a hand-operable lever adjacent the keyboard of the machine, a rockably-mounted thumb-piece at the end thereof, and means for holding said thumb-piece in its horizontal position during the operation of said lever.

11. A sound-deadening casing for a type-writing machine completely enclosing the machine except for the keyboard-extension protruding therethrough, and means for operating the carriage of the machine from the outside of said casing, said means including a hand-operable lever adjacent the keyboard of the machine, a rockably-mounted thumb-piece at the end thereof, and means for holding said thumb-piece in its horizontal position during the operation of said lever, said last-mentioned means including a parallelogrammatic link operatively connecting a downwardly-extending portion of said thumb-piece with a fixed pivot in the wall of the casing upon which the link is rockably mounted.

12. A sound-deadening casing for a portable typewriting machine having a platen relatively near the base of the machine, said casing including a cover and completely enclosing the machine except for the key-

board-extension which projects through an aperture in the front of said casing, and means adjacent the rear of said base for directing the trailing portion of a standard 5 typewriter-sheet upward to form a loop, said means also providing a smooth traveling path for the loop.

13. A sound-deadening casing for a portable typewriting machine having a platen 10 relatively near the base of the machine, said casing including a cover and completely enclosing the machine except for the keyboard-extension which projects through an aperture in the front of said casing, and a plate extending downward over the rear casing-wall and terminating in an upward bend to form a curved channel adjacent the base of said machine for directing the trailing portion 15 of a standard typewriter-sheet upward at the rear of the machine in the form of a loop, said plate presenting a smooth surface to the loop, so that it travels smoothly 20 to and fro with the platen.

14. A sound-deadening casing for a portable typewriting machine having a platen 25 relatively near the base of the machine, said casing including a cover and completely enclosing the machine except for the keyboard-extension which projects through an aperture in the front of said casing, a plate extending downward over the rear casing-wall and terminating in an upward bend to form a curved channel adjacent the base of said machine for directing the trailing portion 30 of a standard typewriter-sheet upward at the rear of the machine in the form of a loop, said plate presenting a smooth surface to the loop, so that it travels smoothly 35 to and fro with the platen, and a second plate associated with the cover and overlapping the top edge of the first plate, said second plate being effective to direct the leading edge of 40 the typewriter-sheet downward at the rear of the machine and into said channel as the 45 line-spacing of the platen proceeds.

15. The combination with a typewriting machine having a traveling carriage, a platen revolvably mounted on said carriage, and a line-spacing lever on said carriage, of a 50 sound-deadening casing for the machine, the position of the carriage as indicated by the regular letter-spacing carriage-scale of the enclosed machine not being readily observable from the outside of the casing, means 55 for operatively connecting the line-spacing lever to an outside crank journaled in the front wall of said casing in a manner to afford the return of the carriage and the line-spacing of the platen when the crank is rotated, a relatively small letter-spacing scale 60 on the outside of the casing in position to be constantly visible to the operator, said scale having graduations proportionate but smaller than the graduations on the regular letter-spacing scale of the machine, and a pointer 65

operated by said crank so as to indicate on said outside scale each letter-space position of the carriage, as shown on the regular scale.

16. The combination with a typewriting 70 machine having a traveling platen-carriage, of a sound-deadening casing, means for operating the carriage from the outside of the casing, a relatively small arcuate scale on the outside of said casing and having a graduation for each letter-space position of the carriage, a pointer mounted to swing in the arc of said scale, and a train of connections between the pointer, the carriage and said carriage-operating means, said train including 75 movement-reducing devices for causing said pointer to move through a relatively small arc and indicate on said scale each letter-space position of the carriage.

17. The combination with a typewriting 80 machine having a traveling platen-carriage and a sound-deadening casing for the machine, of a handle for operating the carriage from the outside of the casing, a drum within the casing in line with the carriage and operatively connected to said handle, and a cord extending directly from said drum to the carriage, said drum and its connections being mounted below the line of travel of 85 said carriage, so as to be cleared thereby. 90

18. The combination with a typewriting machine having a traveling platen-carriage, a line-space lever, and a sound-deadening casing for the machine, of a handle on the outside of said casing, a drum operatively 100 connected to the handle, the top of the drum being below the printing line, an arm attached to the line-spacing lever and having its free end terminating below the printing line, a cord extending directly from said free 105 end of the arm to the drum, and means for maintaining the cord in taut condition between its two points of suspension.

19. The combination with a typewriting machine having a letter-feeding carriage and 110 a sound-deadening casing for the machine, of means for returning the carriage from the outside of the casing, means for indicating each letter-space position of the carriage, said means including a letter-spacing scale 115 on the outside of the casing, a pointer for the scale, a winding drum operatively connected to the pointer, a cord directly connecting said drum to the carriage, and means for maintaining said cord in taut condition between its two points of suspension, thereby 120 causing the pointer to indicate accurately on said scale each letter-space position of the carriage.

20. The combination with a typewriting 125 machine having a letter-feeding platen-carriage, line-spacing mechanism including a lever, a spring for returning the latter to normal position, and a sound-deadening casing for the machine, of a handle on the outside 130

of the casing wall, a drum operatively connected to the handle, a cord directly connecting said drum to the line-space lever, a letter-space scale on the outside of the casing, 5 a pointer for said scale, operating connections between the pointer and the drum, and means for maintaining the cord in taut condition between the drum and the lever, whereby the handle is held in position and 10 the pointer indicates accurately on said scale each letter-space position of the carriage.

21. A sound-deadening casing for a type-

writing machine having a front wall thereof provided with an opening through which a portion of the front of the typewriting machine may extend, a letter-spacing scale mounted on said front wall of the casing, an indicator for said scale, and means for operatively connecting said indicator with the carriage of the typewriting machine to indicate 15 on the scale each letter-space position of the machine relative to the printing point thereof. 20

EDWARD G. ROWLEY.
